US0D1110713S

(12) United States Design Patent (10) Patent No.: US D1,110,713 S
(45) Date of Patent: * Feb. 3, 2026

(54) TOTE BAG

(71) Applicant: Case-Mate, Inc., Atlanta, GA (US)

(72) Inventor: Amber James, Brookhaven, GA (US)

(73) Assignee: CASE-MATE, INC., Atlanta, GA (US)

() Term: 15 Years

(21) Appl. No.: 30/010,437

(22) Filed: Jun. 27, 2025

Related U.S. Application Data

(60) Division of application No. 29/996,304, filed on Mar. 31, 2025, now Pat. No. Des. 1,093,888, which is a continuation-in-part of application No. 29/951,091, filed on Jul. 8, 2024.

(51) LOC (15) Cl. 03-01

(57) CLAIM

The ornamental design for a tote bag as shown and described.

DESCRIPTION

FIG. 1 is a perspective view of a tote bag according to the design.

FIG. 2 is a front view of the tote bag of FIG. 1.

FIG. 3 is a back view of the tote bag of FIG. 1.

FIG. 4 is a first side view of the tote bag of FIG. 1.

FIG. 5 is a second side view of the tote bag of FIG. 1.

FIG. 6 is a top view of the tote bag of FIG. 1; and,

FIG. 7 is a bottom view of the tote bag of FIG. 6.

The broken lines in the drawings show portions of the tote bag that form no part of the claimed design.

1 Claim, 5 Drawing Sheets
